[57] CLAIM

The ornamental design for a multiple view combination bookend and display frame, as shown and described.

DESCRIPTION

FIG. 1 is a front elevational view showing our new design for a multiple view combination bookend and display frame, the rear elevational view being identical thereto;

FIG. 2 is a left side elevational view thereof, the right side being the mirror image thereof;

FIG. 3 is a bottom plan view thereof;

FIG. 4 is a top plan view thereof;

FIG. 5 is a rear elevational view of a modified form of a multiple view combination bookend and display frame shown in FIG. 1;

FIG. 6 is a front elevational view of FIG. 5;

FIG. 7 is a left side elevational view of FIG. 6, the right side being the mirror image thereof;

FIG. 8 is a bottom plan view of FIG. 6; and,

FIG. 9 is a top plan view of FIG. 6.
